Patented Aug. 3, 1926.

UNITED STATES PATENT OFFICE.

GEORGE JEWETT ROCKWELL, OF HUNTINGTON PARK, CALIFORNIA, ASSIGNOR OF
ONE-HALF TO COLIN TIMMONS, OF LOS ANGELES, CALIFORNIA.

PROCESS FOR SEPARATING HYDROCARBONS FROM OIL-BEARING EARTH.

Application filed April 10, 1923. Serial No. 631,171.

This invention relates to a process for separating hydrocarbons from oil bearing earth and has for its object the provision of a process for re-claiming or separating all the hydrocarbons from oil-bearing earth by means of water, steam and agitation in a closed container and correlated open containers.

Another object of the invention is the provision of a process for recovering the more volatile oils from oil bearing earth and then removing the residue of the hydrocarbons from the sand.

Other objects and advantages will become apparent during the course of the following description.

The invention is illustrated by way of example in the accompanying drawings, in which,

20 Figure 1 is a plan view of an apparatus for recovering all the hydrocarbons of oil-bearing earth.

Figure 2 is a side elevation of the same.

Figure 3 is a transverse sectional view 25 taken along the line 3—3 of Figure 2.

Oil-sand is sand saturated with hydrocarbons which approximate 10 percent of naphtha and 60 percent of illuminating oils. Laboratory experiments show that some oil-sands contain by weight 23.5 percent of hydrocarbons when taken freshly from the ground and when exposed to the air in an open vessel for a year lose, by natural evaporation 70 percent of the greater and most valuable part of their hydrocarbon content, and where it has been proposed to separate hydrocarbons from the oil sands in open vessels the volatile oils are lost by evaporation. By my process the oil sands are mixed 30 with water and steam in a closed revolving container to distill off and recover by condensation such oils associated with the hydrocarbons in the oil-sands which are volatile at a temperature of 212 degrees or less 35 or at a higher temperature when steam under pressure is employed.

The distillation of hydrocarbons in the oil sand which are volatile between certain ranges of temperature is carried out in a closed container or still 1 of the horizontal rotary type and which is mounted upon spaced pairs of grooved wheels 2 supported in bearing blocks 3 upon an elevated table 4. The cylindrical container is provided with a

man-hole 5 which provides means for filling 55 or discharging said container when necessary.

An annular spur ring gear 6 is connected to the outer wall of the container 1 and meshes with a gear 7 driven by a shaft 8. 60 Annular tracks 9 are formed at the ends of the container 1 and engage the grooved wheels 2 for supporting the container and aiding in its rotation when the ring gear 6 is driven.

65 A steam pipe 10 connected with a source of steam and provided with a valve 11 enters the container 1 through a packing mounted centrally in the rear end of said container.

As shown more particularly in Figure 3, 70 the steam pipe 10 connects with a series of steam coils 12 which are employed to heat the contents of the closed container 1 indirectly and the steam pipe 10 has also such connections that free steam can be introduced directly into the interior of container 1 by a pipe 59 controlled by a valve 60. The pipe 59 passes through a bearing sleeve 61 extending into said container at this point. The steam pipe 10 is adapted to be mounted 75 in brackets (not shown) for supporting the pipe where it enters the container 1. An outlet pipe 13 passing through packing centrally of the forward end of the container 1 and having its upper end, as shown at 14, 80 disposed adjacent the upper end of the vertical diameter of the container is for the purpose of carrying off the volatile hydrocarbons which have been distilled from the mixture in the container, to a condenser (not 85 shown) which is connected with the pipe 13. A valve 15 in the pipe 13 controls the flow of volatile hydrocarbon from the container. A bracket (not shown) as is usual is adapted 90 to maintain the pipe 13 in position.

95 A pair of open containers 16 and 17 are located on a platform 18 disposed sufficiently below the platform 4 that the residue from the container 1 may be drained through the trap door 5 and through the Y-trough 19 into the tops of the open containers 16 and 17. A valve 20 is disposed at the connection between the legs 21 and 22 of the trough so that both containers 16 and 17 may be fed 100 at the same time from container 1 or the valve may be located in the position shown in Figure 1 for discharging the contents of container 1 into container 16 alone. A re-

versal of the position of the valve will cause the flow of the residue from the closed container to container 17.

The open containers are provided with 5 stirrers 23 located adjacent the bottom and having depending members 24 somewhat similar in construction to a plow-share. The stirrers are mounted at the ends of vertical shafts 25 which are operated by gears 26 meshing with gears 27. The gears 27 are mounted at the ends of the horizontal shaft 28 which is likewise provided with a worm gear 29 meshing with a worm gear 30 on the shaft 8. The relative sizes of the various gears just described will cause a greater speed of rotation of the stirrers and therefore greater agitation of the residue deposited in the open container than is had in the closed container 1. In this case the larger 15 gears 27 will drive the gears 26 at a greater speed.

A branch conduit 31 from the steam pipe 10 connects with a coil 32 which is mounted adjacent the wall of the open containers 16 and 17 and provides means for heating the contents of the container indirectly. Live steam is also introduced directly into the contents of these containers as indicated below. Each of the containers 16 and 17 25 is provided in the bottom portions with a trap door 33 adapted for discharging the contents of the said containers into troughs 34 which conduct the contents to other open containers 35 and 36.

These containers are likewise provided 35 with stirrers 37 which are driven at a slower speed than the stirrers 23 of the first mentioned open containers. The stirrers in open containers 35 and 36 are connected with shafts 38 which are driven by gears 39 in mesh with gears 40. A worm gear 41 on a horizontal shaft 42 upon which the gears 40 are mounted meshes with a worm gear 43 on the shaft 8.

Steam pipes 38^a connected with the coils 32 of the open containers 16 and 17 supply steam to coils 44 mounted adjacent the walls of the open containers 35 and 36, and there are also provided steam connections for introducing free steam as well. Live steam is introduced from pipes 31 to pipes 55, 56 and 56^a to the open containers 16, 17, 35 and 36. The steam to these containers is controlled 50 respectively by the valves 57 and 58.

The containers 35 and 36 are mounted on platforms 45 which are sufficiently below the platform 18 whereby the contents of the open containers 16 and 17 may be drained readily through the trap door 33 to the open 55 containers 35 and 36 respectively. Trap doors 46 located in the bottom of the containers 35 and 36 are adapted to provide means for discharging the contents of these containers.

Conduits 47 are connected with the con-

tainers 35 and 36 whereby the oil which has been removed from the sands may be drained off the water and collected in the container 48. The container 48 is provided with a stirrer 49 driven by a shaft 50 which is provided with a gear 51 in mesh with a gear 52 on shaft 8. It will be seen from this construction that all the rotating mechanism of the structure are driven simultaneously through one shaft. The shaft 8 is driven 75 by any appropriate means which it is not deemed necessary to illustrate since the means for driving the shaft forms no part of the invention.

The process for removing the various hydrocarbons from oil bearing earth such as oil sands is as follows:

Oil sands and water are placed in the container 1 through the man-hole 5 and steam is admitted through the pipe 10 and 85 valve 11 to the coils 12, or free steam may be directly introduced through pipe 59. The shaft 8 is rotated for rotating the container 1, the rotation being sufficient to cause the water and oil sands to be thoroughly 90 churned while being heated through the coils 12 or by free steam introduced directly into container 1 or by both. This operation in the closed container 1 causes the more volatile hydrocarbons to be distilled off and 95 carried through the top 14 of the pipe 13 which is above the level of the liquid and thence to a condenser where the volatile hydrocarbons are collected.

When it has been determined that all the 100 volatile hydrocarbons have been distilled off which would be lost in the open containers 16 and 17, the container 1 is so positioned as to locate the trap door 5 above the Y-trough 19. If it be desired to fill both of the containers 16 and 17 the valve 20 is located in 105 an intermediate position whence the residue of the closed container is discharged into the open tanks. The agitating member 23

being in operation due to the rotation of the shaft 8 and steam being admitted to coils 32, or free steam introduced directly into the containers or by both, the oil will be thoroughly scrubbed off the sand due to the high temperature and the increased agitation. When this step of the process is complete in the open containers 16 and 17 their contents are discharged into the open containers 35 and 36 where the material is more gently agitated and heated less, the agitation being sufficient only to scrub the sand free of the oil which will then rise upon the water in said container. When it has been determined that the step in the process is complete in the containers 35 and 36 the oil floating upon the water in the open container is discharged into the tank 48 where it is again gently agitated to cause the oil to float upon whatever water may be carried into the container 48. Water from the con-

tainer 48 may be readily removed in a manner which is well-known. The water and sand from containers 35 and 36 are discharged through the trap doors 46.

5 It will be noted that my process is continuous since the container 1 may be constantly replenished from time to time in order to supply a sufficient quantity of material to the respective containers 16, 17, 10 35 and 36.

What I claim is:

1. A process for separating hydrocarbons from oil bearing earth, which comprises agitating such material in the presence of 15 water and at the same time heating it by steam above atmospheric pressure, whereby some lighter hydrocarbons are distilled off and recovered and the residual oil being 20 made less viscid and more mobile by being heated is more readily separated from the sand by attrition, and then further, for completing the separation of the oil from the sand, violently agitating and heating at atmospheric pressure the residue from which 25 some of the lighter hydrocarbons have been

recovered and then gently agitating and heating the material at atmospheric pressure to permit stratification of the oil, water and clean sand, the heat being sustained to keep the heavy oil thin so it will rise and stratify above the water and the gentle stirring bringing together the drops of water contained in the oil so that they unite together into larger globules and settle into the body of water beneath the oil, the gentle stirring 35 also freeing the sand from globules of oil which would otherwise be entrapped and carried down with the sand while it was settling to the bottom of the container.

2. A process for separating hydrocarbons 40 from oil bearing earth which consists of partially distilling the oil bearing earth for removal of some of the lighter oils, agitating the materials in the presence of water and steam heat by which oil would be freed from 45 the grains of sand by attrition and gently agitating and heating by steam to permit stratification of the oil, water and sand according to their specific gravities.

GEORGE JEWETT ROCKWELL.
